GEORGE T. CHAMBERS, OF LA GRANGE, ILLINOIS

CAR REPLACER

Application filed February 20, 1929. Serial No. 341,325.

The present invention relates to car replacers and has to do particularly with an improvement in the construction thereof and to the reversibility of the device.

5 Car replacers comprise pairs. Whenever a truck leaves a track, at least two of its wheels, those opposed, are derailed.

In the present instance, the replacer members are paired. They are so constructed 10 that they may be employed from either end. Numerous modified details of construction in the members amount to improvements in the art.

Included in the objects of the invention, 15 among others, are the following:

The provision of an improved configuration for a car replacer;

An unique arrangement of elevating surfaces facilitating the rapid replacement of 20 derailed wheels;

An unique apparatus capable of reversibility and in effect comprising two replacer members uniquely united; and

A new combination of paired car wheel 25 replacers.

These objects, and such other objects as may hereinafter appear, are obtained by the novel construction, unique arrangement, and improved combination of the several elements which constitute the single form of 30 the invention illustrated in the accompanying drawing, in which

Figure 1 is a plan view of the paired replacers shown upon a section of track;

35 Figure 2 is a transverse section on the line 2-2 of Figure 1, looking in the direction of the arrows;

Figure 3 is an inside elevation of one of said members; and

40 Figure 4 is a similar view of the other of said members.

Like reference characters are used to designate similar parts in the drawing and in the description of the invention which follows.

45 As is usual in car replacing devices, one member is unlike the other. One is an "outside" member and the other, the "inside" member. These names will be applied to 50 the present members, such designation fol-

lowing their arrangement in the drawing. The "outside" member is invariably used outside the rails, while the "inside" member is always used between the rails.

The outside member comprises a cast body, 55 generally of steel and hollow, having a top face 10 and a pair of side faces, 11 and 12. One side 11 is substantially straight, and is used in juxtaposition to the left-hand rail 14 shown. Along its abutting edge, adjacent 60 the bottom thereof, is a narrow flange 15 which engages the flange 16 of the rail.

The opposite face 12 comprises an inwardly curved arcuate section 17 coextensive with the top face 10 and having its highest section and most sloping portion intermediate its length, indicated 18. Said face 17 is bounded by a flange 19 through which a plurality of holes 20 to receive spikes 21 adapted to be driven into ties 22 are provided. At a convenient point in this side is an elliptical hand hole 23 facilitating the gripping of the member, the hand being adapted to be inserted therethrough for the purpose of gripping the member while it is grasped for transportation or adjustment. 65

The top face 10 is divided into two sections 24 and 25 which meet adjacent the top. Each has an inclined surface which extends upwardly from the end of the device until it reaches its maximum height at the middle of the replacer. The outer surface 24 has its top point 26 in juxtaposition to point 18 on side 12. 70

In proximity to the highest point 27 on surface 25, the material of the replacer is depressed to form pockets 28, facilitating the return of a car wheel to the rail 14 for, anterior to reaching pocket 28, the flange of the car wheel has been elevated above the top of rail 14. The impetus obtained by the wheel rolling or sliding into pocket 28 guides it with accelerated movement onto and over rail 14, the face 25 sloping away from point 27 and from pockets 28 at such an angle that further movement of the car wheel in the same direction as it is forced up the replacer travel will cause such car wheel to assume its normal position upon rail 14 with the flange thereof on the inside. Adjacent the 75 80 85 90 95 100

higher portion 27 of the top surface 25, the top section 26 of surface 24 is substantially triangular in plan view, the pockets 28 sloping sharply therefrom.

5 The differences in elevation between the upper and lower surfaces 24 and 25 provide a shoulder 29. The body of a car wheel is adapted to travel on the elevated portion 24 and the flange of such wheel travels at some point intermediate the edge of the face 25 and the shoulder 29. A slight slope toward shoulder 29 in face 25 generally causes the flange of the wheel engaging the shoulder 29 for guidance in its upward course, thus 10 deflecting the wheel, at the proper time, into pocket 28 after the flange has been elevated above the rail top.

15 The rounding or sloping of the top of surface 24 adjacent the depression 28 hereinabove referred to as pockets is also for accelerating the replacement of the car wheel upon the rail 14.

Beneath each end of member 10, the material of the device extends inwardly to form 20 a short bottom surface, which bottom surface is traversed by a longitudinal lug or rib 30 extending partly thereacross, and which ribs terminate further from the rail 14 than from the outside edge of the bottom section. Barbs or lugs 31 are arranged beneath side 12 and upon the flange 19 thereof for projection into ties 22.

25 The inside member 40 comprises a cast steel hollow member having a substantially vertical side 41, the bottom edge of which is provided with an inwardly projecting flange 42 which engages a rail 43.

Said member 40 also has an obliquely sloping upwardly extending outside face 44, 30 there being an oval opening 45 therein to the hollow interior of the device. Said side 44 is also provided with a flange 46 through which a plurality of holes 47 are provided for the insertion therethrough of spikes 21 to be imbedded in the ties 22 beneath.

45 The upper surface of the device 44 is divided into opposed upwardly sloping sections 48 which meet at the highest point 49 in the device, and at a point substantially equidistant from each end. There is a slight inward slope of the material at this point.

The sections 48 follow the top edge of the side 44 and the sections possess in plan view a shape much like a bow. As these sections approach the high point 49, they become enlarged and slope inwardly, and extend almost to the inner side 41 of the device.

60 The height of surface 44 is such that the body of a car wheel riding thereon lifts the flange of the wheel higher than the adjacent rail 43, thereby permitting of the wheel riding onto and over the rail 43 when discharged from the replacer 40.

The top surface of the device contiguous to sections 48 is the lowest surface thereof. Such surfaces 50 comprise substantially plane slightly sloping areas extending from the replacer end to the high point 49 of the device, there being an accelerated inward slope of said faces 50 as the top portion thereof is approached.

This slope 51 in said section 50 extends toward the elevated ribs 48, just described, and becomes most pronounced at the inner face 41 of the device adjacent the central section 49 of the elevated surfaces 48.

Two added elevated sections 52 comprise ribs of greatest width substantially midway their length and extend from the end of the replacer upwardly a part of the distance up the sloping face 50 of the device. One edge of such ribs is parallel to the face 41, and each terminates adjacent the sloping section 51.

This arrangement is for the purpose of having the tread of a car wheel ride upon ribs 52, the flange of the wheel being adapted to ride in the space between the two elevated sections 48 and 52. For that reason, too, the dividing shoulder 53 between rib 48 and area 50 becomes less abrupt and more sloping as the top of the device is approached while the shoulder 54 intermediate areas 50 and ribs 52 is abrupt its entire length, sloping out only when in proximity with the sloping section 51. Such slope 51 accelerates a wheel discharge from rib 52 toward and onto the rail 43.

The ribs 48 and 52 give to the area 50 a wide mouth to receive the flange of the derailed wheel, and the narrowing or constricting of the area 50 forces the tread of the wheel onto the shorter rib 52 until the tread of the wheel has been lifted sufficiently to permit of the flange thereof riding over the rail 43 in its journey toward a normal disposition upon said rail.

Like the outside member 10, the inside member 40 has a short bottom end having a transverse lug 55 thereon, such lug extending from substantially the outside of the member thereof to the other edge but not extending all the way thereacross. Adjacent the spike holes 47, the flange 46 has a plurality of barbs or pointed lugs 56 insertable into the ties 21.

When the members are placed in the position shown in Figure 1, and are firmly anchored there through the aid of spikes 21 and the barbs on flanges herein referred to, the derailed wheel or truck on the car or locomotive has been derailed is ready to be moved. The flanges of the wheels are adapted to travel in the lower areas of the members. The treads are adapted to ride upon the elevated surface of the outside member and upon the ribs 52 of the inside member.

Movement of the locomotive or car having the derailed wheel causes the wheels to ride upwardly upon the paired members until they shall have reached substantially the center thereof. At this time, the flanges of the wheels are above the rails, and one of the depressions in the outside member and one of the sloping surfaces 51 in the inside member permits of an added impetus to the locomotive or car which impetus will aid the pulling force upon the car, generally causing the wheels to ride over the rails into their normal position with their flanges between said rails and with the tread of the wheels upon the top surface of the rails.

The length of the members 10 and 40 is such that they are adapted to bridge at least three ties 22 so that there is always sufficient supporting surface for the heaviest of cars or locomotives. In this respect the device possesses inherent advantages over the shorter devices having one replacer section.

Another advantage of this device is that it is adapted to be employed from either end. As shown, the members 10 and 40 are adapted to be used with the wheels derailed to the left, but when wheels are derailed to the right, the members are reversed in relative position as well as in relation to the rails, and may then be used with equal facility.

The space 48 is relatively wide between the shoulders 53 and 54. This facilitates the replacing of a car wheel even where there is a relatively inaccurate "setting" of the device. This takes care of situations where through negligence or carelessness, the device is not closely applied to the derailed wheels and permits of successful use under even the adverse condition of grossly inaccurate positioning of the apparatus.

I claim:

1. A car replacer comprising a pair of elongated members each having two upwardly inclined faces bounded by a marginal rib terminating in a centrally elevated portion extending inwardly from the outside edge of the member and sloping downwardly toward the inside edge thereof, one of said members having a plane surface generally lower than and sloping toward the marginal rib thereon and having a depression adjacent to said centrally elevated portion providing a continuation of the inward slope thereof whereby to provide an arcuate pocket at each side of said centrally elevated portion, said centrally elevated portion having a V-shaped extension projecting from said marginal rib, and the other member comprising a similar lower plane surface with a less sharply defined depression therein and more sharply divided from the rib adjacent thereto, there being in association

with the inner edge of said member an elevated section extending from the bottom of the upwardly inclined face and terminating in said depression.

2. A car replacer comprising a pair of elongated members each having two upwardly inclined faces bounded by a rib terminating in a centrally elevated portion extending inwardly from the outside edge of the member and sloping downwardly toward the inside edge thereof, each of said members having an arcuate side inwardly and outwardly depressed and providing a margin of said rib, one of said members having a plane surface generally lower than and sloping toward said rib, there being a sloping depression adjacent the uppermost section of said lower plane surface providing a continuation of the inward slope of said centrally elevated portion said centrally elevated portion having a V-shaped elevation adjacent its crest, whereby to provide a wheel chute at each side of said elevated portion, and the other member comprising a similar lower plane surface with a sharply defined shoulder adjacent said rib and a less sharply defined depression, there being in association with the inner edge of said member other ribs extending from the bottom of the upwardly inclined face and terminating in said depression.
